(57) **CLAIM**

The ornamental design for an expandable trivet as shown and described.

DESCRIPTION

FIG. 1 is a top perspective view of an expandable trivet showing my new design.

FIG. 2 is a bottom perspective view of FIG. 1.

FIG. 3 is a top perspective view of the expandable trivet of FIG. 1 in the expanded state.

FIG. 4 is a bottom perspective view of FIG. 3.

FIG. 5 is a top view of the expandable trivet of FIG. 1.

FIG. 6 is a bottom view thereof.

FIG. 7 is a front view thereof.

FIG. 8 is a rear view thereof.

FIG. 9 is a right-side view thereof; and,

FIG. 10 is a left-side view thereof.

Portions of the expandable trivet are shown in broken lines.

Portions shown in broken lines form no part of the claimed design.
